UNITED STATES PATENT OFFICE.

HENRY E. BUTLER, OF SCHENECTADY, NEW YORK.

ADJUSTABLE PILLOW-SUPPORT.

1,003,982.

Specification of Letters Patent. Patented Sept. 26, 1911.

Application filed March 10, 1911. Serial No. 613,527.

To all whom it may concern:

Be it known that I, HENRY E. BUTLER, a citizen of the United States, residing at Schenectady, New York, have invented certain new and useful Improvements in Adjustable Pillow-Supports, of which the following is a specification.

The present invention relates to adjustable supports for pillows and equivalent devices, and has for its object to improve and simplify their construction.

In the accompanying drawing which illustrates one embodiment of my invention, Figure 1 is a side elevation of the support, and Fig. 2 is a plan view thereof.

The support comprises three principal elements, a base portion adapted to rest on a mattress or the like, a pillow supporting member, and a prop or means for holding the said member at any desired angle.

The base portion is made of a single piece of heavy wire and comprises two side pieces 1 and 2 and a front piece 3. The rear end of each side piece is turned downwardly at 4 which part is intended to extend between the mattress and the head of the bed to prevent the support as a whole from shifting. The lower ends of the parts 4 may be turned under as at 5 to form an additional securing means. Each side portion of the base is provided with a series of notches 6 made by bending the wire of which it is composed. These notches are suitably spaced apart and are adapted to receive and retain the prop which holds the pillow supporting member. At or about the point where the side pieces 1 and 2 unite with the front piece 3, loops 7 are provided which receive the lower ends of the side bars of the pillow supporting member and prevent them from slipping sidewise along said piece 3.

The pillow supporting member comprises two side bars 8 and 9 and a rear connecting bar 10, all made of one piece of heavy wire. The lower end of each side bar is provided with an eye 11 through which the portion forming the loop 7 in the base extends. The shapes of the loop and eye are such that they form a hinge, the parts of which are free to turn one on the other but cannot slip sidewise. In each side bar at a point about midway of its length is an eye 12 occupying a plane perpendicular to that of the mattress. These eyes are arranged to receive the eyes formed on the supporting means or prop.

The supporting means or prop is made of heavy wire and comprises two side portions 13 and 14 and a connecting portion 15 which is adapted to engage the notches 6 in the base portion. The ends of the side portions 13 and 14 are provided with eyes 16 that pass through the eyes 12 in the pillow supporting member. The plane of these eyes is at right angles to those in said member. Sufficient play is permitted so that the parts will freely turn one with respect to the other.

It will be seen that the pillow supporting member is of the same general shape as the prop or supporting means but somewhat smaller in size so that when the prop is moved out of engagement with the notches 6 the whole will lie perfectly flat on the mattress. The advantage of this resides in the fact that the pillow can be arranged perfectly flat on the mattress when desired and this without removing the support. In other words, the construction of the support is such that the pillow can be raised and lowered as desired without inconvenience to the user, and without removing the support. When the pillow supporting member is down the structure as a whole occupies so little space as not to interfere in any way with the comfort of the user.

It will also be noted that my improved device is thoroughly sanitary, being made of metal, preferably of some non-rusting character. It may be made of iron or steel if preferred and coated with some good hard form of enamel, preferably white for appearance sake. By obviating all spaces or recesses in which dirt and germs may collect, I obviate the danger due to the transmission of disease from one patient to another. Since the support as a whole is made entirely of metal and can be folded into a relatively small and compact space, the structure may be readily immersed in some anti-septic fluid for the purpose of cleaning, and this without in any way injuring it.

The support is particularly suited for hospitals but it will also be found to be of great utility in homes.

What I claim as new and desire to secure by Letters Patent of the United States, is:—

1. In a device of the character described, the combination of a wire base portion comprising two side pieces, each of which is provided with bent wire notches, and a front connecting portion, the said sides and front

100

110

portion being integral, a wire pillow supporting member having eyes that encircle and are hinged to said connecting portion, and a prop that is hinged to the said member and is arranged to fit into said notches.

2. In a device of the character described, the combination of a wire base comprising two side pieces and a connecting front portion integral therewith, each of said side pieces being provided with notches, a pillow supporting member also made of wire and comprising two side pieces and a connecting portion located at the top, each of the side pieces having a bent lower end forming an integral eye and through which the connecting portion of the base extends, and also

a bend located between its ends forming a second eye, and a prop also made of wire and comprises two side pieces and a connecting portion located at the top, each of said pieces having a bend at its upper end forming an eye which passes through the second eye in the side piece of said member, the connecting portion of the prop being arranged to enter said notches. 25

In witness whereof, I have hereunto set my hand this 8th day of March, 1911.

HENRY E. BUTLER.
